Allys

UNITED STATES PATENT OFFICE.

HARRY J. WERTHEIMER, OF CHICAGO, ILLINOIS.

AUTOMATIC WASHER.

Application filed November 16, 1923. Serial No. 675,044.

To all whom it may concern:

Be it known that I, HARRY J. WERTHEIMER, a citizen of the United States, and a resident of the city of Chicago, in the county of Cook and State of Illinois, have invented certain new and useful Improvements in an Automatic Washer; and I do hereby declare that the following is a full, clear, and exact description of the same, reference being had to the accompanying drawings, and to the numerals of reference marked thereon, which form a part of this specification.

This invention relates to an automatic washer and particularly to such a device which is adapted to be operated by the fluid which is alternately applied to the object to be washed.

In washing automobiles and the like, it is desirable that the washing member consisting of a brush, sponge or other suitable soft material be moved over the surface to be washed and that subsequently the dirt and other foreign matter, loosened from said surface by said washing member, be rinsed therefrom.

It is an important object therefore of the present invention to provide an automatic washer of the class described wherein the washing member is operated by the pressure of the washing fluid.

It is also an important object of this invention to provide an automatic washer of the class described which is simple, durable and efficient and which may be economically manufactured.

Other and further important objects of this invention will be apparent from the disclosures in the specification and the accompanying drawings.

The invention (in a preferred form) is shown on the drawings and hereinafter more fully described.

On the drawings:

Figure 1 is a bottom plan view of an automatic washer embodying the principles of this invention.

Figure 2 is an enlarged fragmentary section on the line 2—2 of Figure 1 with parts shown in elevation.

Figure 3 is a section on the line 3—3 of Figure 2 with parts omitted.

Figure 4 is a perspective view of the washing member and propelling turbine.

As shown on the drawings:

The washing member, which is rotatable, is mounted in an annular casing 1 which is

centrally apertured and which is provided with a central outer bracket 2 having a portion spaced therefrom and having an aperture registering with the central aperture in the casing.

The washing member and propelling turbine therefor which are rotatably mounted in the casing 1 will now be described.

Positioned in the casing adjacent the bottom thereof is a flat circular plate 3 which has a plurality of propelling blades 4 extending into the casing from the upper face thereof. Said plate 3 is provided with a central hub or sleeve member 5 which is rotatably mounted on a spindle bolt 6 projecting through the apertures in the casing 1 and bracket 2 and being secured in position relative to said casing and bracket respectively by lock nuts 7 and 8. The blades 4 are provided with a cover member 9 which is of substantially the same diameter as the plate 3 and which is provided with a central discharge opening, the cover member 9 being formed outwardly around said discharge opening as shown in Figure 2 to act in conjunction with the end of the bolt 6 and hub 5 to form a fluid discharge nozzle.

The washing member which is used to rub the surface to be washed is secured to the cover member 9 in any suitable manner, the form which I have shown in the drawings comprising a felt annulus 10 which is provided with a central opening surrounding the discharge nozzle in the cover member 9. Said annulus 10 in the present instance is secured to the cover member 9 by flexible members 11 which are fastened to upwardly struck fastening members 12 on the outside of the cover member. It will of course be understood that the washing member 10 may be constructed of sponge, sponge rubber or may consist of an annular brush member as may be required by the character of washing to be done by the device.

Means are provided for introducing fluid such as water under pressure into the interior of the casing 1 to cause a rotation of the plate 3 and the washing member 10 by the impingement of said fluid against the turbine blades 4 which are attached as previously described to the plate 3. For this purpose an opening 13 is provided in the wall of the casing 1 and connected to said opening 13 is a short-pipe section 14 which in turn communicates with a supply con-

duit 15 through a semi-flexible hose or similar connection 16. The flow of fluid through the supply conduit 15 is controlled by a suitable shutoff valve (not shown) which is 5 mounted in the conduit near the outer end thereof and which may be controlled by a usual valve operating handle 17. The provision of the semi-flexible connecting section 16 makes it possible to reach otherwise inaccessible places such as the underside 10 of fenders, etc., with the washing member.

In using the washer of this invention it is of course only necessary to position the washing member 10 against the surface to be 15 washed and actuate the valve handle 17 to permit a flow of fluid through the supply conduit. The impingement of this fluid against the blades 4 will cause a rotation of the washing member 10 on the surface to be 20 washed, which will have the effect of removing the dirt and other foreign accumulations therefrom and the subsequent discharge of the fluid through the nozzle formed at the center of the cover member 9 will wash away 25 the material which has been loosened by the rotation of said washing member 10. The supply conduit 15 may of course be conveniently connected with any source of supply fluid under pressure and the outer end 30 thereof is provided with a suitable threaded connection 18 for this purpose.

In order that the assembly of the device may be conveniently effected the end of the spindle bolt 6 is provided with a screw slot 35 19 whereby a screw driver may be engaged therewith through the opening in the cover member 9.

The automatic washer of this invention 40 operates very successfully with ordinary city pressure and in cases where only low pressure water supply is available it will be apparent that a suitable power operated turbine pump may be employed to provide the

necessary supply of fluid under pressure to the supply conduit 15.

It will be apparent that the device of this invention may be economically manufactured and it will be further apparent that I have provided means wherein the pressure of the fluid used for washing is utilized in the 50 actuation of a washing member, thus greatly facilitating the washing operation and at the same time effecting the same with economy in the amount of fluid consumed.

I am aware that numerous details of construction may be varied through a wide range without departing from the principles of this invention, and I, therefore, do not purpose limiting the patent granted hereon otherwise than necessitated by the 60 prior art.

I claim as my invention:

A device of the class described comprising a casing, a conduit connected to said casing, a dished disc secured to said casing, a rotatable member within said casing comprising a pair of discs, a plurality of blades secured between said discs extending radially from the center thereof, the upper of said discs having an aperture in the center thereof, the lower of said discs having a smaller aperture in the center thereof, a washing member mounted on said upper disc, a sleeve member mounted on said lower disc, means comprising a bolt, and a pair of nuts one 75 of which is situated on said bolt between said casing and said dished disk, for rotatably securing said rotatable member to said casing.

In testimony whereof I have hereunto subscribed my name in the presence of two subscribing witnesses.

HARRY J. WERTHEIMER.
